LOOM FOR WEAVING PILE FABRIC

Eugene F. Clark, Damariscotta, Maine, assignor
to Marshall Field and Company, Chicago, Ill.,
a corporation of Illinois

Application April 8, 1946, Serial No. 660,573

12 Claims. (Cl. 139—46)

1

My invention relates to looms for use in the weaving of pile fabrics for use in carpets, rugs and the like and also to the fabric itself and has for its primary object the provision of a loom for rapid weaving of pile fabrics and which is practically automatic in its operation and requires very little attention on the part of a weaver except to keep the loom supplied with material, and embodies specifically actuating means for the pile yarn weaving mechanism shown and described in my copending application Serial No. 566,853, filed December 6, 1944, of which this application is a continuation-in-part.

One of the main objects of my invention is the provision of pile weaving mechanisms which can be incorporated into a loom adapted to produce the usual base fabric comprised of the usual warp and filler yarns, and in which the pile weaving means functions and operates with the specific weaving apparatus of a loom which produces the base fabric.

Another and further object of my invention is the provision of a loom for weaving either one shot filler fabric or two shot filler fabric and which can be easily changed from a one shot to a two shot loom in distinction to the usual three shot loom of the Axminster type.

Another and further object of my invention is the provision of a loom in which heavy pile fabric for use as carpets, rugs and the like can be woven rapidly with extremely simple weaves with a body of sufficient weight and thickness to insure proper laying of the fabric on a floor and to insure long wear and lasting qualities.

Another and further object of my invention is the provision of a loom in which an improved fabric is produced both from the standpoint of manufacturer and user, in that I am able to produce a fabric in which the yarn making up the pile is closer together, particularly immediately adjacent the base fabric than is common with fabrics of this type heretofore woven, thereby eliminating the spaces between the tufts of pile and on the surface of the base fabric under which dirt lodges in the use of floor coverings, and in which, when such rugs and carpets are cleaned the cleaner agents can be completely removed thereby eliminating the chance of this material remaining in the fabric causing the fabric to deteriorate, thereby improving the wearing qualities of the fabric and increasing its life.

Another and further object of my invention is the provision of a loom for the weaving of pile fabrics in which the pile is woven in the form of loops simultaneously with the weaving of the fabric with the pile yarn drawn around and in frictional engagement with the fingers thereby providing a backing against which the fabric is "beat up" thereby enabling a more closely woven

and tighter fabric than what has been produced heretofore.

Another and further object of my invention is the provision of pile weaving means which can be combined in many ways with a loom which weaves the usual base fabric comprised of the usual warp and filler in such manner that the pile is interwoven with the base fabric in one complete and continuous operation.

10 These and other objects of my invention will be more fully and better understood and in which:

Figure 1 is a perspective view of the power transmitting mechanism of a loom showing the filler inserting needle and operating means therefor taken from the front of the loom.

15 Figure 2 is a perspective view of a portion of the frame of a loom showing the power means and gear transmission for the operation of a loom taken from the rear of the loom.

20 Figure 3 is a perspective view taken from the front of the loom showing the frame of the loom and a portion of the pile inserting mechanism.

25 Figure 4 is a rear view taken in perspective of the same side of the loom as Figure 3.

Figure 5 is a perspective view of the operating cams and connecting shafts showing particularly the operating parts for the pile guide frames taken from the front of the loom.

30 Figure 6 is a rear perspective view of the operating cams for the pile guide frame and operating parts.

Figure 7 is a detailed elevational view of the one end of the pile inserting guide frame and operating parts therefor.

35 Figure 8 is a detailed elevational view of the pile frame and operating parts therefor for one shot operation.

Figure 9 is a detail of the cam shown in Figure 40 8 with a segment secured thereto for use in the two shot operation of the loom.

Figure 10 is a detail view of one of the fingers, the pile insertion guides and a section of the cloth rest.

45 Figure 11 is a detailed elevational view through a section of one shot fabric slightly expanded to show the relative position of the warp and pile yarn.

Figure 12 is a detailed elevational view through a section of two shot fabric somewhat expanded to show the position of the warp and filler yarns and with all warps at equal tension.

50 Figure 13 is a detailed elevation view through a section of two shot fabric showing the fabric somewhat approximating the completed fabric, with unequal tension warps.

55 Referring now specifically to the drawings and in which like reference characters refer to like parts throughout, a main loom frame 20 is shown having an auxiliary frame 21 at one side thereof

upon which the power supply together with certain of the power shafts and gears are mounted with auxiliary frame members 22 and 23, which are mounted on the frame 20 and extend upwardly from said frame and have the pile yarn beam mounted thereon (not shown) together with certain of the pile yarn weaving mechanism hereinafter described. A motor 24 is provided on the frame 21 having a gear 25 mounted on the motor shaft and in mesh with a second gear 26, which, in turn, is mounted upon a jack shaft 27 upon which a gear 28 is mounted, which, in turn, meshes with a large gear wheel 29 upon the main loom drive shaft 30, this shaft 30 extending across the main frame 20 and the auxiliary frame 21, and through which power for all of the weaving operations is applied to the various operating parts of the loom, either directly from this shaft 30, or indirectly through a gear 31 mounted upon the main shaft 30, which meshes with a gear 32 mounted upon a secondary power shaft 33, which also extends transversely across both the main frame 20 and the auxiliary frame 21 and to which some of the operating parts of the loom are connected. The gear 31 has a ratio of 2 to 1 with respect to the gear 32 so that with each two revolutions of the shaft 30 the secondary power shaft 33 makes one revolution.

Also mounted upon the main power shaft 30 is a bevel gear 34, which meshes with a bevel gear 35 on the end of a shaft 36 upon which a gear 37 is mounted, which, in turn, meshes with a gear 38, which is mounted upon a short axle secured to the auxiliary frame 21, and has a crank arm 39 secured thereto to which a second arm 40 is secured, this arm 40 being secured by means of a stud 41 to a lever 42 pivotally mounted at its lower end to the frame 21 at the front of the loom. A needle guide 43 is provided which is mounted on the auxiliary frame 21 upon an arm 44 by means of a link 45, and at its inner end is mounted upon a bracket 46 secured to the main frame 20 of the loom, the needle guide 43 having a crosshead 47 slidably mounted thereon to which the rear end of a needle 48 is secured, with the front end of the needle 48 passing through a guide 49 secured to the cloth rest 50 of the loom, which, in turn, is mounted upon the main frame 20. A link 51 connects the crosshead 47 with the upper end of the lever 42 so that as the main drive shaft 30 of the loom rotates the lever 42 is oscillated and the needle moved into and out of the shed of the loom, carrying the filler threads into the shed of the loom between the warps during the weaving operation. The gears connecting the main drive shaft 30 with the lever 42 are of 1 to 1 relation with each other and the travel of the needle is continuous except as it reverses its position at each end of its travel, the needle being drawn out a sufficient distance so that as it travels out of the shed of the loom back to a stationary position and then returns to the shed of the warp, sufficient time has elapsed for the beat-up operation to take place and the heddles to shed the warp so that the warp is in position to receive another shot of filling.

Cams 52 and 53 are provided which are mounted on the main power shaft 30 and with rocker arms 54, 54 on a shaft 55 mounted in the main frame 20 with rollers 56, 56 on the ends of the rocker arms 54, 54 operating in closed tracks in the cams 52 and 53 with rocker arms 57, 57 mounted on the shaft 55, on the upper ends of which a reed box 58 is mounted, having the usual reed dents 59 positioned therein. Heddle guides

60 and 61 are provided which are secured to the main frame 20 of the loom and have the usual heddles 62 and 63 slidably mounted in the guides 60 and 61 with rods 64, 64 being provided, which, are connected to the heddles 62 and 63 and to levers 65, 65 pivotally mounted at their rear ends upon a bracket 66, secured to the main frame 20 of the loom and which are actuated by a pair of cams 67 and 68 mounted upon the auxiliary power shaft 33 and which operate to shed the warp threads carried by warp beams in the usual manner upon the main frame of the machine and not shown in the present drawings. These operations are all carried on in synchronism with the operation of the needle 48 and the operation of the reeds 59 to perform the beat-up operations in the weaving of the base fabric. The mechanism hereinafter described is common to various types and kinds of looms for the weaving of the base fabric in pile materials and is all old and well known in the art.

My invention has to do with the pile yarn weaving means and comprises a finger bar 69, which extends across the main frame 20 of the loom and is secured to the heddle bar guides 60 and 61 by means of angles 70, 70, the bar having a plurality of spaced fingers 71, 71 thereon which are inclined downwardly and extend forwardly towards the front of the loom parallel with the warps and in front of the heddles 62 and 63 and terminate immediately above the marginal edge of the cloth rest 50, and in the form shown have blades 72, 72 therein for the purpose of severing the loops of the pile thread after these loops are formed on the fingers 71, 71 as will be more fully hereinafter described. The fingers 71 are notched at their rear ends and fit over a rib 73 extending longitudinally of the bar 69 and are fitted into slots formed in the bar 69 only slightly wider than the thickness of the fingers 71 with a cap 74 fitted over the upper ends of the fingers 71, 71 which is held in position by means of screws 75, 75.

A pair of frames 76 and 77 are pivotally mounted upon shaft 78 journalled in brackets 79 and 80 secured to the inner faces of the upstanding frame members 22 and 23. The members 76 and 77 have channel members 81, 81 thereon at their lower front edges within which a pair of bars 82 and 83 are slidably mounted having a plurality of pile yarn guides 84, 84 therein, these guides having openings 85, 85 in the lower ends thereof through which the pile yarn passes during the operation of the loom. The bars 82 and 83 are slotted at their ends and have bolts 86, 86 extending therethrough in the slots and through the channel members 81, 81 with spacers 87, 87 being provided so that the bars 82 and 83 are normally spaced apart from each other to allow space for the pile yarns to pass between the bars 82 and 83 as they are threaded through the guides 84 in bar 82. The guides 84, 84 are removably mounted in openings formed in the underside of the bars 82 and 83 respectively, and are held in position by means of screws 88, 88. A pair of rods 89 and 90 are provided which are pivotally secured to the members 76 and 77 near the forward ends thereof, and at their lower ends are pivotally attached to crank members 91, 91 mounted upon a shaft 92 which is journalled at each of its ends in bearings secured to the main frame 20.

An arm 93 is attached to the shaft 92 which in turn has a rod 94 attached thereto and which extends rearwardly and is connected to a rocker

link 95 secured at its lower end to a bracket 96 mounted upon the frame 20. A cam 97 is mounted upon the secondary power shaft 33, this cam 97 having two low faces 98 and 99 thereon, and two high surfaces 100 and 101, these surfaces providing a track for a roller 102 which is mounted upon the link 95 so that as the cam rotates, the arm 95 is oscillated, which through its various connections including a spring 103 which is attached to the link 95, causes the members 76 and 77 to oscillate in a vertical plane, thus bringing the guides 84, 84 into and out of the shed of the loom carrying with them pile yarns which are woven into the fabric simultaneously with the weaving of the base fabric, as will be more fully described hereinafter.

Cam guards 104 and 105 are provided which are secured to the main cam by means of brackets 106, 106 and provide a closed cam immediately opposite the high places 100 and 101 provide for smooth operation of the frames 76 and 77 during the operation of the loom. As the roller 102 travels on the lower surfaces 98 and 99 the link 95 moves forward, thereby permitting the frames 76 and 77 to drop into operative relation into the shed of the loom while as the high cam surfaces 100 and 101 reach the roller 102, the frames 76 and 77 are forced upward so that the guides 84, 84 are above the warp and fingers 71, 71 as shown in Figure 10. The operations heretofore described are in timed relation with the needle 48 and the beat-up mechanism during the normal one-shot operation of the loom. In Figure 9 a cam segment 107 is secured to the cam 97 across the low face 99 by means of brackets 108, 108 so that as the cam 97 rotates with the segment 107 attached to it, only one descent of the guides, 84, 84 will be made into the shed of the loom with the rotation of the secondary power shaft 33 and which operates in timed relation with the needle 48 and beat-up mechanism and produces a two shot fabric. In the operation of the loom this two shot fabric is as illustrated in Figures 12 and 13, a fabric in which only alternate shots of filler pass through the pile loops at their bottoms.

Mounted upon the frames 76 and 77 are rolls 109 and 110 in spaced relation with each other, each of which has snap rolls 111 and 112 thereon mounted upon pins 113, 113 in the rolls 109 and 110. Brackets 114 controlled by springs 115 are mounted upon each of the rolls 109 and 110, which with the snap rolls 111 and 112 form a combination which provides means by which the required tension is maintained upon the pile yarn which is threaded around the rolls 109 and 110 and the snap rolls 111 and 112 and the slack in the pile yarn is taken out at the beginning of the ascent of the guides 84, 84 after they have reached the lowermost point of their travel into the shed of the loom and commence the return to their normal position above the warp. A comb 116 having pins 117, 117 thereon in spaced relation with each other is secured to the forward edge of the members 76 and 77 with the pile yarn being fed between the pins or teeth 117 on the comb 116 so that the strands of pile yarn do not become tangled or twisted with each other as they pass to the guides 84, 84.

An arm 118 is provided, one end of which is attached to the bars 82 and 83, the other end of which is attached to a lever 119 pivotally mounted upon a bracket 120 which is secured to the side of the frame 76 the rear end of the lever 119 extending rearwardly between a pair of pins

121 and 122 which are mounted in a block 123 fixed to a shaft 124, the shaft 124 being slidably mounted in a U-shaped member 125 which is secured to the side of the upstanding frame member 22. A bracket 126 is secured to the outer face of the frame member 22, and has a bell crank 127 mounted thereon which is connected to the outer end of the shaft 124 and to a rod 128 secured at its lower end to a lever 129 mounted on the frame 20 at its rear by a connection 130 and has a cam roller 131 mounted thereon intermediate its ends with a spring 132 secured at the free end of the lever 129 at its lower end and anchored upon a pin secured to the frame 20 at its upper end, the spring 132 normally exerting a pull on the lever 129 in an upward direction to keep the cam roller 131 in engagement with a cam 133 secured to the side of a gear 134 mounted upon the secondary power shaft 33.

The cam 133 is bolted to the face of the gear wheel 134 and has a high cam surface 135 and a low cam surface 136, these surfaces being equal in distance around the periphery of the cam 133 which forms a track for the roller 131. The gear 134 is normally secured in fixed rotatable relation with the secondary power shaft 33 by means of a key 137, so that the gear 134 and the cam 133 rotate in synchronism with the secondary power shaft 33 when the loom is in operation in the weaving of the one-shot fabric. A sleeve 138 is mounted on the end of the secondary power shaft 33 with a gear 139 on the outer end thereof, with a shaft 140 being provided which is secured by means of brackets 141, 141 to a frame 142 which in turn is secured to the main loom frame 20 in any approved manner, the shaft 140 having a gear 143 mounted on the outer end thereof with a second gear 144 mounted on the inner end thereof in mesh with the gear 134 on the secondary power shaft 33. The gears 139 and 143 are in 1-1 ratio with each other, while the gear ratio of the gear 144 with respect to the gear 134 is 2-1. A threaded bolt 145 is mounted on a collar forming an integral part of the gear 144, and in the normal operation of the loom when weaving the one shot fabric, this bolt 145 is out of engagement with the shaft 140 although this entire gear train operates, the gear 144 rotates on the shaft 140, although this shaft 140 is rotating it travels at only one half the speed of the gear 144. When it is desired to convert the loom to weave the two shot fabric, the key 137 is removed from the gear wheel 134 and the screw 145 is turned up into engagement with the shaft 140, whereupon the cam 133 is driven through the gears 139, 143 and 144, rotating the cam 133 at one-half the speed at which it normally travels in the operation of the loom for the two shot weave. It will be understood that as shown in Figures 3 and 4, the roller 131 is on the high side of the cam 133 and as the roller 131 travels onto the low cam surface 135, the spring 132 lifts the lever 129, resulting in an upward thrust in the bell crank 127, producing an inward thrust on the shaft 124 and through the bolts 121 and 122, inward thrust on the rear end of lever 119, causing this lever to exert an outward pull on the rod 118, thereby sliding the bars 82 and 83 and shogging the pile yarn guides laterally over the fingers 71, this movement taking place just prior to the time when the roller 102 is about to reach one of the low sides of the cam 97, resulting in the descent of the pile yarn guides 84, 84 into the shed of the loom carrying the

pile yarns with them in which position the needle 45 traverses transversely of the loom, carrying with it the two strands of filler normally used in the base fabric into the open warp and above the pile yarn. As the needle 45 is withdrawn the cam 97 has reached a point where the roller 102 engages on one of the high surfaces of this cam, resulting in forcing the frames 16 and 17 upward and carrying the pile yarn guides 84, 84 out of the shed of the loom. A beating up operation thereupon takes place through the cams 52 and 53 mounted on the main power shaft 30 of the loom.

Mounted upon the cloth rest 50 is a pair of brackets 146 and 147 which have blocks 148, 148 mounted thereon by means of bolts 149 and 150, and upon which a shaft 151 is mounted, this shaft 151 having disks 152 thereon, with spacers 153 mounted between the disks 152 which serves to space the disks 152 apart from each other approximately the same distance as the spacing of the fingers 71, this construction forming a roll which extends across the loom from side to side with the disks 152 passing between the rows of pile loops with the fingers 71 extending between the disks 152 so as to hold the fabric down in place upon the cloth rest 50 and prevents an undue amount of lifting force on the fingers 71 when the pile thread guides 84, 84 ascend, drawing the pile thread yarns around the filler, and because of the tension on the pile thread yarns, exerts a considerable upward pulling force on the fingers and tending to lift the fabric upward away from the cloth rest 50 unless some means is provided for holding the fabric down taut upon the cloth rest.

The usual let off and take up mechanism is employed which is operated by cams 153 (Fig. 3) and 154 (Fig. 5) on the main loom power shaft 30, these elements being common to all looms and form no part of my present invention. Likewise, particularly in Figure 1, a lever 155 is shown which is connected to a clutch which is connected through a series of shafts and levers to a clutch mechanism, which clutch mechanism connected with the gear wheel 26 is mounted on the jack shaft 27, which mechanism forms a convenient means for the operator to start and stop the loom and which mechanism is common to all looms and forms no part of my present invention.

The fabric as woven on the loom heretofore described is illustrated in Figures 11 to 13 inclusive of the drawings. The warp and filler beams, as well as the warp, filler and pile yarn, are not shown in the drawings illustrating the loom, because the warp and filler beams are standard equipment and their position and relation to the loom are well understood by those skilled in the art. If the warp, pile and filler yarn were shown in the drawings, the various working parts of the loom would be obscured and it is believed the operation of the loom and the weave can be readily understood by those skilled in the art of weaving.

The fabric as illustrated comprises groups of warps, each group consisting preferably of four warps *a*, *b*, *c* and *d*, each group being spaced a short distance from the adjacent group so as to receive the pile yarn *e* between each group of warps, producing rows of tufts *f*, with the warps *a*, *b*, *c* and *d* being grouped close together, and so positioned in the loom that one of the fingers 71 is immediately above the center of each of those groups of warps. The pile yarn is carried

into the shed of the loom at one side of the fingers 71 and at one side of each group of warps so the warps *a* and *d* of each group are in contact with the sides of the pile yarn. Alternate warps 5 are shedded in the same direction by the harnesses, the warps *a*—*c* being controlled by one harness, while the warps *b*—*d* are controlled by the other harness, so that the warps *ac* are parallel with each other, while the warps *bd* are also parallel with each other in the weave illustrated in Figures 11 and 12.

Even tension is maintained in all of the warps shown in Figures 11 and 12 with tufts *f* anchored around each shot of filler composed of two cords *gg* made of strong material, preferably jute, and which is placed in position by the needle 45 and anchored into selvage edges on each side of the fabric mechanism common to looms of this type and which forms no part of my present invention. Because of the fact that the filler cords are very strong and are securely anchored at each side of the fabric, as the pile yarn is woven into the fabric and beat up the warps are pressed tightly together at *hh*, the points where they cross each other because of the shedding operation performed by the heddles, until slight recesses are formed at the sides of the warps within which the next adjacent warps are partially embedded, producing tension in the woven fabric to a slight degree in a fillerwise direction and binding the tufts *ff* tightly in the fabric at their sides. In the use of one shot fabric, the bases of the tufts *f* are in abutting relation with each other in a warpwise direction, and because of the fact that the fabric is beat up against the friction of the pile yarn about the fingers 71 as hereinafter described, as well as the tension of the warps, a very tight weave is produced, in which the tufts *f* are firmly secured and cannot easily be removed.

In the two shot weave illustrated in Figure 12, with all of the warps under equal tension, instead of the bases of the tufts *f* being in engagement with each other, a shot of filler *gg* is placed on the fabric and as it is beat up against the base of the preceding tuft *f*, and on its opposite side has the next succeeding rows of tufts *f* beat up against it, thereby anchoring the tufts and providing a slightly heavier base and slightly lighter pile than what I have illustrated and described with reference to the one shot fabric illustrated in Figure 11.

In Figure 13 a two shot weave is illustrated in which the arrangement of the warps is the same 55 as in the weaves heretofore described with the exception that certain of the warps *a* and *c* in the form illustrated are placed under greater tension than the warps *b* and *d*, preferably the warps *b* and *d* being under about one-half of the tension applied to the warps *a* and *c*. The tension of the warps *a* and *c* is determined by the weaver and may be slightly in excess of that usually used upon all of the warps in normal weaves of pile fabrics, and I have found that with the alternate 60 warps being about one-half the tension of the warps *a* and *c*, that when the warps *a* and *c* are shedded up, the pile yarn inserted and the shot of filler placed in position, with the slack warps under the shot of filler passing through the pile loops, this filler will be low in the fabric. Upon the next shedding of the warps, the loose 65 warps are up, the taut warps down, the filler is placed in between these warps and beat up into engagement with the pile yarn above its base, and also forming a backing against which the

next succeeding row of pile yarn loops is positioned, thereby in effect locking the pile loops in the fabric and making their removal well nigh impossible, and at the same time providing a heavy base fabric which lies flat on a floor and provides a substantial body for the fabric.

In operation the loom is simple and will be understood as designed for continuous operation as long as materials are supplied to it, with the warps being supplied from beams, usually two or more in number mounted on the rear of the frame 20, in the usual manner, preferably with the warps *a* and *c* being carried by one beam, and the warps *b* and *d* by another, and in the case of fabric illustrated in Figure 13 this arrangement of the warp beams is necessary in order that different tension be applied to different sets of warps. The warps pass through the heddles 62 and 63, and are grouped as herein above described, while filler yarn is supplied to the loom and inserted into the warp by means of the needle 48, this combination being old and well known in the art.

The pile yarns are supplied from a beam usually mounted in the frame portions 22 and 23 with the strands preferably threaded under the snap roller 112, over the roller 109, around and under the snap roller 111 and over the roller 110, between the teeth 117 on the comb 116, and thence through the guides 84, the strands preferably being divided, alternate strands passing behind the bar 83 and threaded forwardly through the eye 85 in the guides 84, 84 mounted in the bar 83 while the other strands are threaded between the bars 82 and 83 and forwardly through the eye 85 in the guides 84, 84 in the front bar 82. In the form shown two strands of fiber yarn are simultaneously inserted in the shed of the loom and the two bars 82 and 83 are shifted in unison during the operation of the loom.

It will be understood that the operation of all of the parts which co-operate to form the base fabric is continuous, which includes the needle 48 and the beating up mechanism including the reed dents 59, both of which are operated from the main drive shaft 30, while the heddles 62 and 63 are operated from the secondary power shaft 33 in timed relation however with the operation of the needle 48 and beat up mechanism, and that the operation of the pile yarn weaving parts, with which my invention is primarily concerned is timed to work in synchronism with the continuous operation of the base fabric weaving mechanism.

Assuming that the loom is weaving the one-shot fabric illustrated in Figure 11, and for purposes of illustration a complete cycle of operation of these loom parts takes place with each completed function of all of the mechanism, it will be understood that the secondary power shaft 33 makes only one revolution while the main power shaft 30 revolves twice, due to the gear ratio of the gear wheels 31 and 32, and that the needle 48 makes one complete in and out movement with each revolution of the main shaft 30. As the needle 48 is withdrawn from the warp, the cam 133 functions through the roller 131, lever 129, rod 128 and connections to the bars 82 and 83 to move these bars 82 and 83 and pile yarn guides 84 laterally to a position directly above the spaces between the fingers 71, 71. Simultaneously with this operation, and as the needle leaves the shed warp a beat up stroke is made beating up the shot of filler *gg* left by the needle 48 and the warps are shedded. As the warps are shedded

the roller 102 is starting to ascend in one of the high sides of the cam 97 and through its connections to the frames 76 and 77 these frames descend bringing the pile guides 84, 84 between the fingers 71, 71 carrying the pile yarns with them over the tops of the fingers 71, 71 and forming loops thereover, because the pile yarns are always anchored in the fabric on the opposite sides of the fingers 71, 71 between which the guides 84, 84 descend due to the previous shifting of these guides.

The guides 84, 84 descend into the shed of the loom below the path of travel of the needle 48, and dwell there momentarily while the roller 102 remains on one of the low surfaces of the cam 97. During this dwell the needle 48 makes an in and out movement, placing a shot of filler in between the shedded warps and into the V-shaped space formed by the guides 84, 84 and pile yarns extending below the fingers 71, 71, the shot of filler being in front of the guides 84, 84 and behind the strands of pile yarns. As the needle 48 is withdrawn the roller 102 runs onto one of the high sides of the cam 97, forcing the frames 76 and 77 upward with the guides 84, 84 out of the shed of the loom. As the guides 84, 84 ascend, the pile yarns are drawn around the under side of the filler *gg*, which is drawn up snugly against the under side of the fingers 71, 71, while the pile yarns are also drawn snugly over the fingers 71, 71 in the form of loops. There is some slack in the pile yarns during the first inch or two of travel upward of the guides 84, 84, but this slack is soon taken out of the pile yarns and it becomes taut with the continued upward movement of the guides 84, 84. As the guides 84, 84 ascend, the beat up mechanism again functions, the filling including the pile loops are beat up against the fabric previously woven, and against the usual tension of the warp, and because of the frictional engagement of the loops of pile yarns around the fingers 71, 71 a fairly solid background of fabric is produced against which the beat up operation takes place, thus enabling a much tighter woven fabric to be produced than what has been possible heretofore. Each pile yarn thus is beat up on itself at its front and rear at the base, with pressure by the warps on each side as herein above described, so the pile yarn is very firmly anchored in the base of the fabric, although the weave is a simple one.

While the beat up operation is taking place, the warp is shedded by the heddles, the rod 128 is pulled downward, and through the bell crank 127 and its connections to the bars 82 and 83, these bars are shifted in a right hand direction as shown in Figure 3 of the drawings, so the guides 84, 84 are again over one of the spaces between the fingers 71 but on the opposite side of the fingers 71 against which the pile yarns are laying. Again the roller 102 is reaching one of the low sides of the cam 97, the frames 76 and 77 descend, the needle 48 makes an in and out movement, the frames 76 and 77 ascend, and these operations combine with the bars 82 and 83 shogging the pile yarns over the fingers 71, 71 with each operation of the frames 76 and 77. In each complete cycle of operation with the functioning of all of the elements two shots of filling are placed in the fabric, and two rows of pile loops are formed on the fingers 71, 71, the main drive shaft 30 revolves twice and the secondary power shaft 33 revolves once.

In weaving the fabric illustrated in Figures 12 and 13, the segment 107 is secured to the cam 97 over one of the low surfaces so this cam 97 is

11

converted into a cam having only one low surface extending approximately one fourth of the distance of the periphery of this cam. The key 137 is removed from cam 135 and the bolt 145 tightened so the gear wheel 144 is in fixed engagement with the shaft 140. These changes in the cam 97 result in the guides 84, 84 making only one descent into the shed of the loom with each rotation of the secondary power shaft 33, and because only one descent is made, the bars 82 and 83 are shifted only once, thereby shogging the pile yarns just prior to such descent, so only alternate shots of filling have pile loops placed around them, the shots of filling not through the pile loops forming binders for the bases of the pile loops. The weaving for each of the fabrics illustrated in Figures 12 and 13 are the same in each instance, the difference in the level of the filler in the weaves being produced by less tension on one set of warps than on the other as heretofore explained.

In the weaves illustrated in Figures 11, 12 and 13 as the base fabric is woven, and pile yarns are interwoven therewith simultaneously with the weaving of the base fabric, the pile yarn strands are shogged back and forth on the fingers and then carried into the warp by the guides 84, 84 on alternate sides of the fingers 71, 71 where the pile yarns are interwoven with the warp and filler into a series of loops over the fingers 71 which are successively formed and as the beat up operations combine and the fabric is formed the loops are forced along the fingers towards the ends thereof until they reach the knives where they are severed through their tops thus producing the usual pile on fabrics of this type and kind. The fingers 71 are in effect interwoven in the fabric with the pile loops being in engagement therewith at their tops and sides while the filler is in frictional engagement with the underside of these fingers thus providing a background against which subsequent formations of the fabric are beat up. The pile yarns are in continuous strands in the fabric after it is woven until severed by the knives in the fingers 71 and is therefore under control until firmly woven in the fabric thus producing a tight weave. If loop pile is desired, then the knives are omitted from the fingers 71, 71 and the loops formed on these fingers pass over the ends without being severed.

It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

I claim:

1. In combination with a loom, a plurality of spaced fingers extending warpwise of the loom, a pair of frames vertically movable on the said loom, a pile thread guide bar slidably mounted on said frames, pile thread guides in said bar, means whereby the said pile thread guides are shogged to various positions over the said fingers and means whereby the said frames are moved in vertical planes thereby carrying the pile thread guides into the shed of the loom.

2. In combination with a loom, a plurality of spaced fingers extending warpwise of the loom and in fixed relation therewith, vertically reciprocating frames on said loom, a pile thread guide bar slidably mounted on said frames, pile thread guides mounted in said guide bar, means operated by the power mechanism of the loom whereby

12

the said bars are shifted laterally on said frames and means whereby the pile thread guides are moved into and out of the shed of the loom at predetermined times:

3. In combination with a loom having a reciprocating needle for insertion of the filler yarn as the fabric is woven, a plurality of spaced fingers mounted at one of their ends on said loom and free at their other ends substantially spanning the space between the loom heddles and the cloth rest on the loom, a pair of vertically movable frames, a pile thread guide bar on said frames laterally movable thereon, spaced pile thread guides in said bar, means connected with the power mechanism of the loom whereby the guides are moved laterally on said frames at predetermined times, and means whereby the pile thread guides are moved into and out of the shed of the loom in synchronism with the operation of the filler yarn insertion needle.

4. In combination with a loom having a reciprocating needle for insertion of the filler yarn as the fabric is woven, a plurality of spaced fingers mounted at one of their ends on said loom and free at their other ends substantially spanning the space between the loom heddles and the cloth rest on the loom, a pair of vertically movable frames, a pile thread guide bar on said frames laterally movable thereon, spaced pile thread guides in said bar, a rotating cam on the power shaft of the loom, and connections from said cam to said pile yarn guide bar whereby the said pile yarn guide bar is shogged over the said fingers, a second cam on the power shaft of the loom, connections therefrom to the said movable frames whereby the pile thread guides are moved into and out of the shed of the loom, both shogging operation and movement of the guides into the shed of the loom being in timed relation with the operation of the filler yarn inserting needle.

5. In combination with a loom having a reciprocating needle for the insertion of filler yarn as the fabric is woven, a plurality of spaced fingers mounted at one of their ends and free at the other extending parallel with the warp threads, a pair of movable frames, pile thread guide bars slidably mounted on the forward end of the said frames, pile thread guides mounted in the said bars, a plurality of rotating cams actuated by the power shaft of the loom, connecting means from one of said cams to the said frames whereby the said pile yarn guides are moved into and out of the shed of the loom, and connections from the other of said cams to the pile yarn guide bars whereby the said guide bars are slidably moved on the said frames, both of these latter operations being performed in synchronism with the operation of the reciprocating needle.

6. In combination with a loom having a reciprocating needle for the insertion of filler yarn as the fabric is woven, a plurality of spaced fingers mounted at one of their ends and free at the other extending parallel with the warp threads, a pair of movable frames, pile thread guide bars slidably mounted on the forward end of the said frames, pile thread guides mounted in the said bars, a plurality of rotating cams actuated by the power shaft of the loom, connecting means from one of said cams to the said frames whereby the said pile yarn guides are moved into and out of the shed of the loom, connections from the other of said cams to the pile yarn guide bars whereby the said guide bars are slidably moved on the said frames, both of these latter operations being

performed in synchronism with the operation of the reciprocating needle, and means whereby the operation of the cams can be changed to alter the timing of the shogging of the pile yarn guides and their descent and ascent into the shed of the loom.

7. In combination with a loom having means for the insertion of filler yarn during the weaving process, a plurality of fillerwise spaced fingers mounted on the loom at one of their ends and free at their other ends extending parallel with the warp, vertically movable frames on said loom, a plurality of pile yarn guide bars mounted for sliding fillerwise movement in said frames pile yarn guides in said bars, a rotating cam on a power shaft of said loom, a lever operated by said cam, a bell crank, connections from the bell crank to the pile yarn guide bars, a rod connecting the lever with said bell crank whereby the pile yarn guides are shogged over the said fingers, a second rotating cam on a power shaft of the loom, and operating connections actuated by said second cam whereby the pile yarn guides are moved into and out of the shed of the loom at pre-determined times.

8. In combination with a loom having means for the insertion of filler yarn during the weaving process, a plurality of fillerwise spaced fingers mounted on the loom at one of their ends and free at their other ends extending parallel with the warp, vertically movable frames on said loom, a plurality of pile yarn guide bars mounted for sliding fillerwise movement on said frames pile yarn guides in said bars, a rotating cam on a power shaft of said loom, a lever operated by said cam, a bell crank, connections from the bell crank to the pile yarn guide bars, a rod connecting the lever with said bell crank whereby the pile yarn guides are shogged over the said fingers, a second rotating cam on a power shaft of the loom, and operating connections actuated by said second cam whereby the pile yarn guides are moved into the shed of the loom in advance of the travel of the filler yarn inserting means and withdrawn from the shed of the loom after the filler inserting means has passed out of the warp whereby the filler yarn is looped around the filler yarn.

9. In combination with a loom having a filler yarn inserting needle operable therewith, a plurality of spaced fingers extending warpwise of the loom mounted on the loom at one of the ends, a pair of vertically oscillating frames on said loom, pile yarn guide bars slidably mounted on said frames at their forward ends, pile thread guides in spaced relation with each other and with respect to the said fingers in said guide bars, a cam on a power shaft of the said loom, operating connections from said cam to the said frames whereby the pile yarn guides are caused to travel into and out of the shed of the loom at pre-determined times, a second cam on a power shaft of the loom, connections between this second cam and the guide bars whereby the pile yarn guides are moved fillerwise on said frames, the fillerwise movement of the pile yarn guides being prior to their descent into the shed of the loom and the descent of the pile yarn guides being before the operation of the filler inserting needle and retained in the shed during the travel of the needle into and out of the shedded warp, whereby the pile yarn is woven into a series of loops around the said fingers and the filler yarn.

10. In combination with a loom a pile yarn inserting mechanism comprising a pair of verti-

cally movable frames, pile yarn guide bars slidably fillerwise on the forward ends of the said frames pile yarn guides in spaced relation with each other in the said bars, fingers on the said loom extending parallel with the warps in spaced relation with each other, the spacing of the fingers and the spacing of the pile yarn guides being the same, operating connections with the power mechanism of the loom whereby the pile yarn guides are shogged over the fingers at pre-determined times, and operating connections with the power mechanism of the loom whereby the pile yarn guides are intermittently forced into and out of the shed of the loom at pre-determined times, the shogging of the guides always preceding the descent of the pile yarn guides, and the descent and ascent of each pile yarn guide being in the same plane.

11. In combination with a loom a pile yarn inserting mechanism comprising a pair of vertically movable frames, pile yarn guide bars slidably fillerwise on the forward ends of the said frames pile yarn guides in spaced relation with each other in the said bars, fingers on the said loom extending parallel with the warps in spaced relation with each other, the spacing of the fingers and the spacing of the pile yarn guides being the same, operating connections with the power mechanism of the loom whereby the pile yarn guides are shogged over the fingers at pre-determined times, and operating connections with the power mechanism of the loom whereby the pile yarn guides are intermittently forced into and out of the shed of the loom at pre-determined times, the shogging of the guides always preceding the descent of the pile yarn guides, and the descent and ascent of the pile yarn guides being in the same plane, each succeeding descent and ascent of the guides being in different planes.

12. In combination with a loom a pile yarn inserting mechanism comprising a pair of vertically movable frames, pile yarn guide bars slidably fillerwise on the forward ends of the said frames pile yarn guides in spaced relation with each other in the said bars, fingers on the said loom extending parallel with the warps in spaced relation with each other, knives in said fingers, the spacing of the fingers and the spacing of the pile yarn guides being the same, operating connections with the power mechanism of the loom whereby the pile yarn guides are shogged over the fingers at pre-determined times, and operating connections with the power mechanism of the loom whereby the pile yarn guides are intermittently forced into and out of the shed of the loom at pre-determined times, the shogging of the guides always preceding the descent of the pile yarn guides, and the descent and ascent of the pile yarn guides being in the same plane.

EUGENE F. CLARK.
